(57) **CLAIM**

The ornamental design for an enema bucket device, as shown and described.

DESCRIPTION

FIG. 1 is a perspective view of an enema bucket device, showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing in the enema bucket device illustrate portions of the enema bucket device that do not form any part of the claimed design. The enema tubing is shown with a symbolic break in its length. The appearance of any portion of the article between the break lines form no part of the claimed design.
